(57) **CLAIM**

The ornamental design for an ergonomic adjustable wrench, as shown and described.

DESCRIPTION

This patent application is related to one or more of the following patents granted to the inventor herein: U.S. Pat. No. 604,139; U.S. Pat. No. 7,047,845; U.S. Pat. No. 6,959,628; U.S. Pat. No. 6,792,833; U.S. Pat. No. D. 494,833; U.S. Pat. No. 6,655,239; U.S. Pat. No. D. 481,613; U.S. Pat. No. 6,615,694; U.S. Pat. No. 6,484,610; U.S. Pat. No. 434,956; U.S. Pat. No. D. 414,996; Taiwan 207,794 and 221107; China ZL03155502.0.; and, Canada 2,412,131 and 2,419,354. FIG. 1 is a top rear perspective view of an ergonomic adjustable wrench showing my new design; FIG. 2 is front elevation view thereof; FIG. 3 is a rear elevation view thereof; FIG. 4 is a top plan view thereof; FIG. 5 is a bottom plan view thereof; FIG. 6 is a right side elevation view thereof; and, FIG. 7 is a left side elevation view thereof.
